Primary Examiner—Charles A. Rademaker

(74) Attorney, Agent, or Firm—Gifford, Krass, Sprinkle,
Anderson & Citkowski, P.C.(57) **CLAIM**

The ornamental design for dental pliers, as shown and described.

DESCRIPTION

FIG. 1 is a side elevation of a dental pliers showing my new design;

FIG. 2 is a top perspective view thereof shown on a slightly enlarged scale;

FIG. 3 is a front elevation thereof;

FIG. 4 is a rear elevation thereof; and,

FIG. 5 is a top plan view hereof.

The broken lines shown in the drawings represent environmental structure and do not form a part of the claimed design.
